UNITED STATES PATENT OFFICE.

WILLIAM I. CASSELMAN, OF VERNON, NEW YORK, ASSIGNOR TO ELIAS A. SWAN, OF NEW YORK, N. Y.

MACHINE FOR CARVING MARBLE, STONE, &c.

Specification of Letters Patent No. 11,286, dated July 11, 1854.

To all whom it may concern:

Be it known that I, WILLIAM I. CASSELMAN, of Vernon village, in the county of Oneida and State of New York, have invented, made, and applied to use certain new and useful Improvements in Machinery for Carving Marble and other Substances; and I do hereby declare that the following is a full, clear, and exact description of the construction and operation of the same, reference being had to the annexed drawings, making part of this specification, wherein—

Figure 1, is a plan, Fig. 2, is an end elevation and Fig. 3 a side elevation of the apparatus used for carving with a revolving bed.

The other figures are separately referred to and the like marks of reference designate the same parts.

It will be evident that the article to be carved receiving either a rectilinear or circular motion, and the tool receiving a horizontal as well as a vertical motion almost any figure can be produced by the tool; hence attempts have heretofore been made to effect carving both of wood moldings and other articles by giving these movements to the tool and bed. Therefore this does not constitute my invention, but the nature of my said invention consists in so arranging and applying adjustable pattern wheels in connection with a moving bed carrying the material to be operated on that the said wheels shall communicate a horizontal or vertical motion or both to the tool or cutter which performs the work.

It must be borne in mind that in order to accomplish carving of any desired character there must be a great variety of pattern wheels, and they will have to be applied in a variety of ways to accomplish the carving often of a single piece of work; hence the necessity of showing several ways in which the adjustable pattern wheels may be used to produce the various required forms of carving.

In the drawing Figures 1 to 7 show the machine as fitted for use to form either plain or ornamental marble table tops or similar articles.

A are the sides and a, the cross pieces of bed frame.

a¹ is a shaft set in bearing in the bed frame and having a pinion 1, near the mid-

dle thereof between the frames to which competent power is to be applied to drive the machine. On one end of this shaft a¹ is a miter wheel 2, gearing to a similar wheel 3 on a vertical shaft 4, the lower end of which shaft is stepped in a frame or box b, and the upper supported in the cross piece or head block b¹ which is sustained on the upper ends of the vertical slides, b².

c, is a gear wheel on the shaft 4, communicating through gear wheels c¹ and c² a rotary motion to the circular bed d¹, which is set on a center 5, in the bed plate d, that is supported by and attached to the cross pieces a, of the main bed plate.

6 is a miter gear on the opposite end of the shaft a¹ to the wheel 2, gearing into a similar wheel 7, on the vertical shaft 8, which is supported by a step 9, at the bottom and by the cross piece b¹ at top, so that the shafts 4 and 8 travel at the same speed.

e, is a cross bar so set in the slides b² that it can be moved up and down as hereafter detailed. This bar is beveled back on the top and bottom edge to receive the sliding rest e¹ which carries the cutting tool 10. This tool may be of any desired shape so as to form a square cut or may be shaped so as to form a molding.

e² is an arm attached to the slide rest e¹ projecting through the sides in which the bar e, is sustained, and terminating as a point e³ as shown in Fig. 4, which is a plan of the same and of the end of the pattern wheel which acts on the arm.

f is a fixed wheel or disk on the shaft 8, having attached to the face thereof pattern plates 11, of any desired shape, and the width of the end e³ of the arm is to be such as to come in contact with these patterns, whether the bar e, is raised or depressed.

12 is a spring or similar means to keep the end e³ against the patterns 11.

It will now be seen that if a block or slab of marble is secured to the bed d¹ and power applied to revolve said bed, the gearings being properly proportioned, the tool 10, will be slid in and out cutting into said marble or other material in a compound curved or zigzag edge to the circle described by the revolution of the bed, and by so timing the revolutions of the pattern wheel and bed plate, and attaching the necessary patterns to the pattern wheel f any desired shape of

table top, with a plain edge or with a molded edge according to the shape of the tool can be cut out and also that oval or other shaped picture frames can be formed in the 5 same manner, or any similar character of work produced. And a spring to return the end of the arm against the pattern wheel may be dispensed with by having the arm e^2 extended toward the shaft 4, and terminated with a similar end to the end e^3 and 10 operated on by patterns 13, on the pattern wheel h , which revolving in unison with the wheel f , can be made to follow up the slide rest e^1 and keep the end e^3 against the patterns 11, the pattern 13, being properly 15 formed for that purpose.

In cutting or carving circular as well as straight work it is often necessary to raise the tool from the surface at certain times 20 and depress it at others so as to vary the depth of cut, or lift the tool to pass over raised work; to accomplish this purpose I attach two slings g, g , one on each end of the bar e , which pass down with a guide fork 25 on each side of the shaft a^1 .

g^1 are arms at right angles from the slings (which may be made adjustable vertically if found necessary) projecting over adjustable pattern wheels g^2 , these pattern wheels 30 are made in a similar manner to the wheels f and h , having pattern plates attached thereto, which plates can be adjusted or changed as required, so as to give the requisite lifting motion to the sliding gate or 35 tool rest.

In carving marble and other substances it is often necessary both with a revolving as 40 well as with a sliding bed to use a tool to groove into or plow up the surface and then cut under the edge of the groove or recess so as to relieve the work from the surface; to effect this operation I construct a tool similar to that shown in Figs. 1, 2 and 3, and in larger size in Fig. 5.

45 15, is an arm with the point 16, to the pattern 13, on the wheel h , and 14, is a sliding tool rest on the bar e , attached to the arm 15. The attachment between the arm 15 and slide may be made adjustable by slots and 50 screws if necessary, so as to place the tool rest in the proper position, and this may also be done at the connection between the arm e^2 , and sliding rest if so required.

On the tool rest 14, I attach, by means of 55 a screw countersunk from the inside of the rest so as to move the same out of a vertical line if required, a stock 17 that carries a shaft 18, through bearings in the stock, on the upper end of which is a worm wheel 19 60 in which a worm pinion 20, works, which pinion is supported in journals on the stock 17, and has a handle or other means by which the worm pinion is rotated to turn the shaft 18, into any desired position; on 65 the lower end of this shaft is a tool stock i ,

carrying a horizontal cutter 21, on the bottom and a cutter 22, on the side, both of which are to be of any desired shape, and attached by screws or similar means.

The operation of this part is that the tool stock can be so set as to cut a groove or recess into the marble or other substance, either by a sliding or rotary motion, and then by giving the tool a partial rotary motion on its shaft 18, the groove or recess can be 70 widened and the cutters be made to plow under the edge of the recess, and if the edge of the cutter 22, be molded, a bead or molding may be formed on the edge of the recess, and by using the adjustable pattern wheels 75 in connection with the cutter a zigzag or corrugated cut or groove can be produced, and the stock i , might be extended on the opposite side of the shaft 18, and similarly fitted to cut on both sides of a groove if 80 required. And either one or both of the cutters can be used at once, or a cutter similar to the tool 10, can be attached in place of the undercutting knife so as to cut on the 85 two sides of any article at once, thereby the 90 machine can be made to cut both sides of a molding or table top, or any similar article in the required curved lines.

It will be evident that various kinds of 95 adjustable pattern wheels may be used, the patterns being attached in various ways to the wheels, some of these are shown in Figs. 6, 7, and 8.

The pattern wheel f , may have adjustable points 25, attached to it as in Fig. 6, and the 100 end of the arm e^2 formed with a box 24, into which blocks or patterns 23, are placed, and secured by a screw. These blocks may be of any desired shape so as to give the tool the required movement as the point passes 105 over the ends of said blocks and moves them, or in place of these blocks adjustable rollers may be used to avoid friction on the points. And the body of the pattern wheel may be 110 perforated as shown in Fig. 7, so as to receive a pattern block on its circumference secured by a screw passing through the rim of the wheel into the block.

In cutting marble table tops and similar 115 articles from a slab of marble or other material, the outline is often required to be a series of arcs of circles, therefore I have designed the pattern wheel shown in plan and elevation in Fig. 8, for the purpose of avoiding friction although the same shape may 120 be obtained by fixed patterns but with more friction. In this figure k , is the fixed part of the wheel with slots and adjustable pins 27, carrying rollers l , which can be set in any desired position and l^1 is a disk or wheel set 125 so that it can revolve around the center shaft, the effect of which arrangement is that when the end e^3 comes in contact with any roller or wheel it will move on its center and give the curved motion to the tool and 130

avoid the friction consequent upon the rubbing surface of a solid pattern on the end of the arm.

It will be evident that by having a pattern corresponding to the shape of table top set on the head block b^1 , central over the bed d , and causing the pattern and bed to revolve together, the table top or similar article would be easily formed of the shape of the pattern, 10 the tool being kept to the pattern.

Fig. 9, is a plan and Fig. 10, is an end view of the manner in which I fit my carving machine for performing straight work and combine my pattern wheels with a reciprocating motion. The whole of the parts except the rotary bed and gearing (which are removed) are the same and before described, and act in the manner before detailed, when the block of marble or other 20 substance has a rectilinear reciprocating motion, therefore need no further description.

c , is the sliding bed or carriage moving on ways 28, and the pinion 1, taking a rack on the under side of the bed propels the same 25 back and forth any distance required, the pinion receiving the necessary alternating motion for that purpose by suitable means. The parts will thus perform straight carving of moldings according to the shape of 30 the tool, and when the pattern wheels are brought into use to operate upon the tool, a corrugated or zigzag form may be produced either vertically or horizontally or both combined, according as the pattern wheels are 35 brought into operation.

In cases where a spiral or zigzag spiral are required to be placed on a column or similar article I suspend the same on centers in the head blocks m , m^1 , attached to the bed 40 so that a column can be fluted or otherwise figured in a straight line by successively running the bed and column n , back and forth beneath a properly formed tool, and a zigzag can be formed by the use of the pattern wheels to move the tool laterally. And 45 the column hanging on centers can be rotated as the bed proceeds to receive a regular or zigzag spiral.

n^1 , n^2 , and n^3 , are gears to rotate the column set on an arm 29 from the head block m^1 . The gear n^3 , setting around and sliding on a shaft 30 with a long key allows the gear to be carried along with the bed; this shaft receives motion by means of gears o , 55 o^1 , from the shaft 8, and set in bearings 31.

Having thus described the method in which I use my adjustable pattern wheel in connection with a circular or reciprocating bed I will now proceed finally to show 60 the method in which I apply one single revolving pattern wheel by means of levers to place the tool or tools in the desired position by communicating both a sidewise and vertical motion to said cutters or tools.

65 Fig. 11, is a plan of the parts with the

head block b^1 , and other parts not used in this motion removed. Fig. 12, is an end view, and Fig. 13, is a side view of the wheel with movable patterns.

p is a miter wheel on the shaft 4, matching to a similar wheel 32, or the end of a shaft 33, supported in bearings 34 and having a wheel 35, on the other end gearing to a similar miter wheel q , on the end of a cross shaft 36, that is supported in adjustable boxes 37 in standards r , secured to the main frame A. 70

s , is a wheel on the shaft 36, on the edge and sides of which pattern blocks or plates are attached by screws or similar means to 80 form when moving the tools the shape desired to be cut, which the wheel in its revolution operates on the tools through levers as next set forth.

t , t^1 , are slides receiving the cross bar t^1 , 85 to the ends of which bar levers u , u^1 , are jointed and said levers are set on a cross shaft 38, supported by links v , to the frame, which shaft forms the fulcrum for the levers, and the other ends of the levers are 90 bent and joined together over the circumference of the pattern wheel at 39, so as to communicate to the bar t^1 , a vertical movement and raise or depress the cutters. Of course the pattern wheel has to be the reverse of the shape to be cut so as to allow the tool to raise (by a weight or spring) 95 when the end 39 enters a concavity in the pattern wheel.

40, is a fulcrum on the shaft 38, carrying 100 the levers w , in the form of tongs that receive motion at the ends 41, from the side patterns on the wheel s , and the shorter ends are connected by ball and socket joints or similar means to the sliding rests, x and x^1 , 105 on the bar t^1 . The ends 40, are kept against the patterns by springs or similar means. The rests x , x^1 , carry tools of any desired size or shape, and by means of the movable patterns on the wheel s , the tools can be 110 placed in any required position either horizontally or vertically, and by the use of this arrangement any desired shape can be produced, the material to be operated on receiving a reciprocating motion on the bed. 115

By the use of adjustable or movable patterns a great variety of shapes can be obtained by composing the figure required on the pattern wheel or wheels. Thus a variety of angles, arcs of circles, points, rollers and other shapes can be attached for a given purpose, thereby avoiding the cost of solid wheels for each variety of pattern; and where solid wheels are used the machine has to be taken apart to a great extent to vary 120 the pattern cut, but in my case all that is necessary is to unscrew one set of patterns and substitute another in place thereof, thereby saving much expense and loss of time in changing the machine. 125

- I do not claim moving a cutter by means of solid pattern wheels as this has been done, but I am not aware of any apparatus heretofore used in which adjustable or movable 5 patterns have been attached to a fixed wheel and so combined with a revolving or reciprocating bed, that cutters are thereby brought to operate on the marble or other material to carve the same as specified.
- 10 Therefore what I desire to secure by Letters Patent is—
1. I claim the means herein described and shown for carving or cutting marble or other material consisting of the adjustable 15 or movable blocks or patterns on a revolving wheel or wheels, for determining the position of the cutting tool or tools either horizontally or vertically, in combination with a revolving or reciprocating bed as specified.
  - 20 2. I claim communicating motion from a pattern wheel or wheels, constructed with

movable or adjustable patterns, both on the circumference and on the sides, to the sliding tool or tools by means of levers so set and operating as to place said tools in the 25 required position as the parts move as specified.

3. I claim constructing a cutting tool or tools for carving marble or similar substances with blades or tools 21, 22, attached 30 to the bottom and side of the stock *i*, which stock is so fitted as to receive a rotary motion to operate as specified.

In testimony whereof I have hereunto set my signature this thirty first day of January one thousand eight hundred and fifty four.

WILLIAM I. CASSELMAN.
